UNITED STATES PATENT OFFICE.

MARTIN FEYBUSCH, OF NEW YORK, N. Y.

TAKE-OFF DEVICE FOR GUMMING-MACHINES.

1,355,219.

Specification of Letters Patent. Patented Oct. 12, 1920.

Application filed December 10, 1919. Serial No. 343,776.

To all whom it may concern:

Be it known that I, MARTIN FEYBUSCH, a citizen of the United States, and resident of the borough of Manhattan, city, county, and State of New York, have invented certain new and useful Improvements in Take-Off Devices for Gumming-Machines, of which the following is a specification.

The present invention relates to machines for applying adhesive to sheets of paper or other material and especially to machines of the type known as "pick-off" machines in which an adhesive applying roll or its equivalent is constantly supplied with a coating of adhesive and the sheets are coated with adhesive by contact with such roll from which they are stripped when coated by a so-called "pick-off" device.

Such machines comprise usually a gumming roll, feeding mechanism for feeding sheets separately against the gumming roll and a pick-off or stripper device for removing the sheets from the roll after the adhesive has been applied.

The invention has for an object primarily to provide an improved pick-off device for such machines for stripping the coated sheets from the gumming roll but the arrangement provided is of such a character that it may be used advantageously with various other machines in which a similar function is to be accomplished. Such uses of the arrangement are contemplated as within the scope of the invention.

The problem presented is apparently simple but in fact particularly involved and difficult.

Reliability and continuity of operation of the machines are essential. For example, under usual conditions of use, interruption of the output of a machine causes idleness of several operatives to whom gummed labels are supplied by the machine to be applied while wet to boxes and the like. Furthermore, the machines must operate effectively and reliably without frequent adjustment or repair by a skilled mechanic. This is essential because such machines are operated by unskilled labor and under such conditions that it is impracticable to have them attended by skilled mechanics.

The pick-off device, to be successful, must operate effectively, for example, to strip relatively thin paper labels from the gumming roll, and must do this continuously hour after hour without the necessity for

stopping the machine and thus interrupting its use and permitting the adhesive to dry and harden thereon. The wet labels are soft and yielding and adhere with considerable tenacity to the surface of the rolls, especially when a particularly thin coating of adhesive is being applied. The pick-off points bear upon the rotating roll and gradually wear so that burs form upon the points against which the sheets catch and tear or crumple, thus clogging the machine. To avoid this, provision must be made for repeatedly sharpening the points. Furthermore the pick-off points are usually arranged in a series across the machine and relatively close together, for example, four pick-offs for each inch of width of the machine. As the pick-offs wear and are sharpened, the points tend to get out of alignment with each other. As a result the wet labels are unevenly engaged and are torn or wrinkled, thus causing defective operation or clogging of the machine.

The present invention provides a pick-off device which is at once perfectly effective and reliable in use, easily sharpened and maintained in adjustment, and simple in construction. The invention will be best understood from the following description of an illustrative embodiment thereof. The various features of the invention are in part explained in this specification and in part will be obvious to those skilled in the art.

In the drawing in which I have illustrated a selected embodiment of the invention:

Figure 1 is a side view of a pick-off device constructed in accordance with the invention, shown as applied to a gumming machine, the gumming roll and associated parts being shown diagrammatically;

Fig. 2 is a top plan view of the pick-off device shown in Fig. 1;

Fig. 3 is a sectional view taken on the line 3—3 of Fig. 2.

In the drawing I have shown the gumming roll 5, feed rolls 6 for feeding labels or other sheets against the gumming roll, and a conveyer belt 8 onto which the coated labels are delivered. These parts are substantially the same as shown in my prior Patent No. 1,279,311 granted September 17, 1918, and are shown merely diagrammatically herein for the purpose of illustrating the manner of use of the pick-off device. The device illustrated consists of an arm 9

2
pivoted upon a suitable support 10 and carrying a relatively fixed guide 11 and an adjustable pick-off blade 12.

The guide 11 ordinarily need not be adjustable, and for the purposes of this specification is shown and will be described as fixed in one position in the pivoted arm or holder 9. The angle formed between the sheet engaging edge of the guide and the surface of the roll may vary within wide limits but preferably it is such that the pressure of the sheets, even when relatively thick material is being coated with adhesive will not cause the pick-off finger to be raised away from the gluing roll. As shown, the guide engages a shoulder 13 on the holder and is secured in position by a screw. The pick-off point or blade is adjustably mounted in the holder as for example in a slot 15 and is held in adjusted position by a clamping screw 16. The arm thus constitutes a holder on which are carried a fixed guide and an adjustable pick-off point or blade. The shape of the blade is such that, as it is sharpened and reset it is merely fed forward and the position of the upper sheet engaging and guiding edge 17 of the blade relative to the guide does not change. Proper coöperation of the guide and pick-off blade is thus assured.

The holder 9 is of sufficient weight to cause the pick-off point to maintain contact with the gumming roll during operation of the machine. The pick-off blade is formed to present a sharp point 18 in contact with the roll. Its lower face 19 is arranged to be substantially tangent at the point of the blade to the surface of the roll 5, such arrangement maintaining the point in close contact with the roll while at the same time providing a substantial bearing to resist wear. It is contemplated that the pick-off blade will be sharpened repeatedly as the

point wears and before any substantial bur forms thereon.

The shape of the blade as shown is such that the point may be readily sharpened by filing the lower face 19 thereof. This should preferably be done in a jig which insures maintenance of the desired angle. It is necessary for best operation that all the pick-offs on the particular machine be set with the same adjustment, both in order that the pick-off points may all be maintained in correct alinement with each other and also in order that the most efficient angle between the pickoff point and the surface of the roll may be maintained.

To insure such accurate setting of the pick-off blade in the holder, it is preferably always set both originally and after resharpening in a jig or gage provided for the purpose. Inasmuch as the exact predetermined position of the holder when the pick-off point rests upon the roll is assured, on account of the arrangement of the adjustable blade as above explained, the position of the guide relative to the gumming roll and therefore relative to the conveyer is assured.

Variations in the details of the arrangement illustrated will readily occur to one skilled in the art.

I claim:

In a machine of the character described, a pick-off device comprising a pivoted arm or holder, a guide secured to said holder, and a pick-off blade adjustably mounted in said holder constructed and arranged to be sharpened and to be readjusted to maintain the point and guiding edge thereof in constant predetermined relation to the holder.

In testimony whereof I have hereunto set my hand.

MARTIN FEYBUSCH.
